UNITED STATES PATENT OFFICE.

THOMAS CARPENTER SMITH, OF PHILADELPHIA, PENNSYLVANIA.

BRACKET FOR ELECTRIC LAMPS.

SPECIFICATION forming part of Letters Patent No. 453,248, dated June 2, 1891.

Application filed May 19, 1890. Serial No. 352,337. (No model.)

To all whom it may concern:

Be it known that I, THOMAS CARPENTER SMITH, a subject of the Queen of Great Britain and Ireland, and a resident of Philadelphia, Pennsylvania, United States of America, have invented certain new and useful Improvements in Converter-Brackets, of which the following is a specification.

My invention relates to brackets for electric wires, and particularly to brackets for suitably supporting shunt-coils and the connecting-wires.

My invention is illustrated in the accompanying drawings, wherein—

15 Figure 1 is a side view of a pole to which both brackets are applied. Fig. 2 is a similar view at right angles. Fig. 3 is an enlarged detail of the bracket and shunt-coil box. Fig. 4 is a perspective view of the shunt-coil bracket. Fig. 5 is a detail of the shunt-coil box.

Like parts are indicated by the same letters in all the figures.

20 A A are the poles, having the cross-arms B B, to the outer end of one of which is secured the shunt-coil bracket. This bracket consists of the arms C C, with the vertical piece D. The arms carry the insulators E E, to which the main-line conductors F F are secured.

25 G is a shunt-coil box, having the insulators H H, whereby it is secured to the vertical piece D by means of the screw-hooks J J. The conductors K K lead from the insulators 30 E E down to the lamp, and loops L L from them lead into the shunt-coil. In like manner loops M M lead from the main conductors to the shunt-coil. At the junction of the arms C C and the piece D are the ledges N N, between 35 which a place is formed for securing the entire device to the end of the cross-bar. The 40 loops or wires M M are connected within the

shunt-coil box by a resistance, and each wire L is connected with its adjacent wire M within the box in the usual manner in such shunt-coil boxes. The resistance shunts sufficient current to the lamp below to sustain it. 45

Should the main line break at its insulators the loop-wire through the shunt-box will hold it up sufficiently to keep the lights on 50 the line going until proper repairs can be made. In the event of the breaking of the wires which lead to the lamp, if the break occurs at the top above the connection of the wire L with the wire K, the lamp below will 55 not be extinguished, while if it breaks near the bottom of wire K the only disadvantage will be the extinguishing of that particular lamp. However, the invention has relation to the structure of the bracket and 60 the connections of the wires and posts rather than the operation of the lights.

Having thus described my invention, what I claim, and desire to secure by Letters Patent, is—

65 1. A bracket provided with two pairs of arms, each at right angles to the other, one pair angular and adapted to receive the conductor-insulators, the other pair provided with screw-hooks adapted to receive the insulators upon which the shunt-box is fastened. 70

2. The combination of a bracket with insulators for the main conductor, a shunt-coil secured to but insulated from said bracket, conductors connecting the coil with the main 75 conductors, conductors connecting the coil with the lamp-loop, and conductors for the lamp-loop from the main conductors near the insulators on such brackets, substantially as described.

THOMAS CARPENTER SMITH.
